UNITED STATES PATENT OFFICE.

WILLIAM J. PLATTEN, OF GREEN BAY, WISCONSIN.

BEEHIVE.

Application filed March 16, 1922. Serial No. 544,235.

To all whom it may concern:

Be it known that I, WILLIAM J. PLATTEN, a citizen of the United States, and a resident of Green Bay, in the county of Brown and State of Wisconsin, have invented a new and useful Improvement in Beehives, of which the following is a full, clear, and exact description.

My invention relates to improvements in bee hives, and it consists in the combinations, constructions, and arrangements herein described and claimed.

An object of my invention is to provide a bee hive of the character described which is constructed for use out-of-doors in cold regions so that a minimum loss of bees through freezing and starvation and a minimum consumption of honey is brought about. This is accomplished by constructing the walls of an insulating material by proportioning the air passages to the amount of air needed by the bees in consuming the honey and by the use of a moisture condensation control arrangement.

25 A further object of my invention is to provide a bee hive of the character described, in which the entrance may be varied, i. e., a small entrance for the winter time and a large entrance for the summer.

30 A further object of my invention is to provide a device of the character described which is compact in form and the interior made readily accessible, and which is relatively cheap to manufacture, easy to assemble, and compact for shipping knocked-down.

Other objects and advantages will appear in the following specification, and the novel features of the invention will be particularly pointed out in the appended claims.

My invention is illustrated in the accompanying drawings, forming part of this application, in which

Figure 1 is a perspective view of an embodiment of my invention showing the parts disassociated,

Figure 2 is a sectional view of the rear ventilating duct,

Figure 3 is a partial longitudinal section 50 of the hive, and

Figure 4 is a perspective view of one of the interchangeable entrance blocks.

In carrying out my invention, I make use of a bee hive comprising a hive body 1 having four sides. The material of the body is 55 preferably solid pressed cork board or any other suitable insulating material. An inner wall 2 is disposed within the wall 1 and cemented thereto by an interposed layer of asphalt cement 3.

60 Adjacent the lower edge of a side 4 of the hive body is a rectangular recess 5. The recess 5 is adapted to receive a rectangular block member 6, in which an entrance block 7 is removably disposed. The entrance 65 block 7 is provided with a passage 8 therethrough. In Figure 1, I have shown a relatively small passage 8, while in Figure 4, I have shown another of the blocks 7 in which a relatively large passage 9 is shown. This 70 large passage is for use in the summer time and the block having the small passage 8 is for use in the winter.

The passages 8 and 9 in the blocks 7 provide also an entrance for air in ventilating 75 the hive. A second ventilating duct is provided in the rear wall 10 of the wall 1. With reference to Figure 2, it will be noted that the wall 10 is provided with an inwardly extending passage adjacent its upper surface 80. and with a groove 11 on its inner side. The inner wall 12 of the wall 2 is also provided with a groove 13 similar to the groove 11, which groove is in registration with the groove 11 and the passage 14 communicating with the grooves 11 and 13. This structure provides a ventilating duct and is arranged to co-act with the passages 8 or 9 of the block 7 to ventilate the hive.

85 A cover 15 of cork board or other suitable material is provided and arranged to rest upon the top of the hive body substantially as shown in Figure 3. The cover 15 is provided with a pair of transversely disposed metallic strips 16 adjacent the forward and rear ends thereof. A plurality of metal ribs 17 having their sides parallel to one another are mounted at each end upon the metallic strips 16. The ribs 17 are fashioned so that their under edges slope from the central 100 portions thereof downwardly, as they approach their ends. This is more clearly shown in Figure 1.

A bottom 18 is provided and is also con-

structed of solid pressed cork board or other suitable material. The bottom 18 is arranged to closely engage and support the hive body. A metal pan 19 is supported 5 upon the bottom 18 and of such size that it will cover the floor of the hive when the body 1 is in place. The pan 19 is provided with a grating 20 thereupon, which grating is composed of a plurality of non-metallic strips 21, bound in spaced apart relation to one another by transverse rods 22. The purpose of this grating 20 is to prevent the bees from lighting upon the water which might be condensed in the pan 19. The forward 10 portion of the grating 20, as shown at 23, is provided with a smooth floor so that the bees in entering through the passages 8 of the entrance blocks will not come into contact with the sharp up-turned edges of the strips 15 21. This grating is non-metallic so that no condensation will collect on it, but will drop through to the metal pan.

In Figure 3, I have shown a standard type of honey frame 24, which may be supported longitudinally in the hive upon rabbed portions 25 of the end walls. The entire exterior of the hive is coated with a heavy coating of asphalt cement so as to waterproof the hive.

From the foregoing description of the various parts of the device, the operation thereof may be readily understood. In the summer-time, my bee hive is used just as any other bee hive using the block 7^a only, 30 or with the blocks 6 and 6^a additional. In the winter, when in use, the pan 19 is placed upon the bottom 18 and the block 7, having the small passage 8, is used in addition to the blocks 7^a, 6, and 6^a to further restrict 35 the opening. Furthermore, in the ordinary hive, condensation of moisture in the hive will occur directly upon the bottom surfaces of the hive cover and the water will drip upon the honey and upon the bees. This 40 condition presents a severe disadvantage in that the comb becomes wet and moldy. In my construction, the moisture condenses 45 upon the metal ribs 17 and is carried because of the inclined lower edges thereof 50 and toward the ends of the frame 24 where it drips into the pan 19. Water and frost collected in the pan 19 is out of the way of the bees.

The use of solid cork board in the construction of my hive gives a high inherent insulation for the interior, that is, the heat transference per degree of temperature difference between the inside and the outside, will be very slow compared with any of 55 the present single or double walled type of hives.

57° F. has been determined as the lowest temperature of hive interior at which the bees are semi-dormant (not eating, breathing 60 very little). When the hive gets colder

than this, the bees consume enough honey to give them sufficient energy by rapid wing movement to increase the temperature again to 57°. In my hive, they will not have to eat as much honey because the heat is held 70 inside and not radiated so freely as in the old style hives.

The size of the contracted entrance 8 and the rear ventilating duct was determined by the amount of air needed by the bees in 75 the consumption of twenty pounds of honey over a winter of 130 days, with a circulation slow enough so that there would be no draft effect. The use of cork board construction gives a self-supporting structure 80 of the insulating material itself.

I claim:

1. A bee hive of the character described comprising side walls of heat insulating material, a plurality of interchangeable entrance blocks adapted to fit an opening in one of said side walls, said blocks having passages therethrough of various diameters, and a ventilating passage of a predetermined diameter in the opposite of said side walls. 90

2. A bee hive of the character described comprising side walls, a cover, a bottom wall, metal strips disposed longitudinally upon the inner surface of said cover, said strips having their lower edges inclined 95 downwardly adjacent the opposite ends thereof, and a metal pan disposed on the bottom wall of said bee hive.

3. A bee hive of the character described comprising side walls, a cover, a bottom wall, metal strips disposed longitudinally upon the inner surface of said cover, said strips having their lower edges inclined 100 downwardly adjacent the opposite ends thereof, a metal pan disposed on the bottom wall of said bee hive, and a plurality of interchangeable entrance blocks, each having a passage therethrough of a different 105 predetermined diameter, said blocks adapted to fit an opening through one of said side walls. 110

4. A bee hive of the character described comprising side walls, a cover, a bottom wall, metal strips disposed longitudinally upon the inner surface of said cover, said strips having their lower edges inclined 115 downwardly adjacent the opposite ends thereof, a metal pan disposed on the bottom wall of said bee hive, a plurality of interchangeable entrance blocks, each having a 120 passage therethrough of a different predetermined diameter, said blocks adapted to fit an opening through one of said side walls, and a ventilating passage of a predetermined diameter in the opposite of said side 125 walls.

5. A bee hive of the character described comprising side walls, a cover, a bottom wall, metal strips disposed longitudinally upon the inner surface of said cover, said 130

strips having their lower edges inclined downwardly adjacent the opposite ends thereof, a metal pan disposed on the bottom wall of said bee hive, a plurality of inter-changeable entrance blocks, each having a passage therethrough of a different predetermined diameter, said blocks adapted to fit an opening through one of said side walls, a ventilating passage of a predetermined diameter in the opposite of said side walls, and non-metallic floor grating resting on said pan.

WILLIAM J. PLATTEN.
